CANOPY FRAME FOR BED

Kenneth H. Gutner, 3285 Dato, Highland Park, Ill.

Continuation-in-part of design application Ser. No. 147,305, May 26, 1971. This application Dec. 6, 1972, Ser. No. 312,587

Term of patent 14 years

Int. Cl. D6—06

U.S. Cl. D6—198

FIG. 1 is a top plan view of the inventive canopy frame;

FIG. 2 is a side elevational view of the frame of FIG. 1;

FIG. 3 is an enlarged perspective view showing one of the two identical side rails of the frame in greater detail; and

FIG. 4 is an enlarged fragmentary perspective view of an end of one of the rails of the frame.

The design is characterized by the configuration of the end portion of the rail, as is best illustrated in FIG. 4.

This application is a continuation-in-part of my co-pending application Ser. No. 147,305, filed May 26, 1971.

I claim:

The ornamental design for a canopy frame for bed, as shown and described.
